Primary Examiner — Ricky Pham(74) *Attorney, Agent, or Firm* — Hanrahan Law Firm, P.A.; Benjamin M. Hanrahan(57) **CLAIM**

The ornamental design for a milk frother, as shown and described.

DESCRIPTION

FIG. 1 is a front perspective view illustrating my/our design for a milk frother.

FIG. 2 is a rear perspective view thereof.

FIG. 3 is a left side view thereof.

FIG. 4 is a rear view thereof.

FIG. 5 is a right side view thereof.

FIG. 6 is a front view thereof.

FIG. 7 is a top view thereof, the size of which is enlarged 20 percent as compared to FIGS. 1 through 6 to show detail; and,

FIG. 8 is a bottom view thereof, the size of which is enlarged 20 percent as compared to FIGS. 1 through 6 to show detail. The broken lines shown in the Figures illustrate portions of the article that form no part of the claimed design.
